UNITED STATES PATENT OFFICE.

HARRY HOISINGTON AND FRANK HARGENS, OF DAVENPORT, IOWA.

SUPPORT FOR SINGLE-FRONT TARGETS.

Application filed April 8, 1924. Serial No. 705,146.

(GRANTED UNDER THE ACT OF MARCH 3, 1883; 22 STAT. L. 625.)

To all whom it may concern:

Be it known that we, HARRY HOISINGTON and FRANK HARGENS, citizens of the United States, and residents of Davenport, in the 5 county of Scott and State of Iowa, have invented an Improvement in Supports for Single-Front Targets, of which the following is a specification.

The invention described herein may be 10 used by the Government, or any of its officers or employees in prosecution of work for the Government, or by any other person in the United States, without payment to us of any royalty thereon, in accordance 15 with the act of March 3, 1883.

The subject of the present invention is a support for a single front target.

In marking a single front target, it is necessary to lower the target from the upper 20 or firing position to a lower or marking position where the target will be accessible to the marker. Where the lowering is accomplished by hand apparatus considerable labor is involved due to the necessity for 25 marking the target after the firing of each string and where mechanical means are employed for moving the target to and from firing position great difficulty has been experienced in maintaining such means at all 30 times in proper working order.

The present invention aims to overcome the difficulties heretofore experienced in marking targets of the single front type by providing mechanism which can be actuated 35 to move the target to and from firing to marking position and which is automatically reset during movement of the target so as to be in position for further movement of the target.

40 A further object of the invention is the provision of means for locking the target in firing position which is adapted to be retained in locking position by the actuating mechanism.

45 A further object of the invention is the provision of a target supporting frame work so secured to the supporting post as to minimize the tendency of a twist in the post throwing the frame out of line.

50 With the foregoing and other objects in view, our invention resides in the novel arrangement and combination of parts and in the details of construction hereinafter described and claimed, it being understood

that changes in the precise embodiment of 55 the invention herein disclosed may be made within the scope of what is claimed without departing from the spirit of the invention.

A preferred embodiment of our invention is illustrated in the accompanying drawing, 60 in which;

Fig. 1 is a front elevation of a target support constructed according to our invention;

Fig. 2 is a side elevation thereof;

Fig. 3 is an enlarged detail view of the 65 actuating mechanism;

Fig. 4 is a side elevation of the drum;

Fig. 5 is a front elevation of the same; and

Fig. 6 is an enlarged view of the locking 70 pawl.

Referring to the drawing by numerals of reference:

We have shown a post 5 adapted to carry the frame work of the target support. This 75 post 5 may be of any suitable size and the supporting mechanism employed with the same is of such a type, as will be described hereinafter, as to permit the use of any log or post which may be found handy on the range. The materials to be carried, to the 80 range, therefore, are reduced to a minimum.

Carried at the lower end of the post is a crossbar 6, adapted to support at either side of the center thereof guide bars 7 which extend parallel with the post. These guide 85 bars 7 are secured at their upper ends to a second crossbar 8, which is secured to the frame work 9 attached to the upper end of the post.

Slidably mounted upon the guide bars 7 is 90 the target supporting frame work 10, which may be of any suitable type but which, as shown, is constructed, preferably, of a pair of parallel angle irons provided with registering apertures adapted to receive the 95 uprights 7 and secured in spaced relation to each other by straps 11 upon which are mounted the sockets 12 for the target frame. A plurality of such sockets will preferably be provided spaced at varying distances 100 apart so that, as is clearly shown in Fig. 1, different sizes of targets may be used with the same frame work.

To move the target supporting frame 10 from upper or firing position to the lower or marking position and return, we have found it preferable to provide mechanism which will automatically reset itself during such

movement. This mechanism includes a drum 13 rotatably mounted upon the supporting frame 9. To one end of the drum is secured a sprocket 14. Wound around the drum in the upper or lower position of the target is a flexible member 15, which may be a strap or chain. A second flexible member such as a chain 16 is adapted to pass over the sprocket and engage with the teeth thereof. This chain is fastened at one end to the lower crossbar of the target supporting frame 10 and has secured to its other end a counterweight 17 of suitable size. As will be obvious unwinding of the flexible member 15 from the drum will cause movement of the chain 16 over the sprocket to move the target. By providing a flexible member 15 of a length equal to substantially half the travel or range of movement of the target, the member 15 will, during movement of the target, automatically reverse itself on the drum and thereby reset itself for further movement of the target, the target being carried on to the limit of its movement by its own momentum.

Any suitable means may be employed for enabling the target marker to unwind the flexible member 15 from the drum and thereby impart an initial movement to the target. We, preferably, employ a treadle 18 for this purpose which is preferably pivotally mounted upon a beam 19 fastened to the post 5 adjacent its lower end. Pivoted to the end of the treadle arm is a connecting rod 20, which moves in guides 21 secured to the side of the post. A ring or other connecting member 22 secured to the outer free end of the flexible member 15 and slidable upon the connecting rod 20 serves to connect the flexible member 15 with the treadle so that movement of the treadle will cause unwinding of the strap 15.

For locking the target in its upper or firing position, we have found it preferable to provide a pawl locking member 23 pivotally mounted upon the frame 9 and so constructed as to be moved by gravity to locking position. For maintaining this locking member in locking position, we have found it preferable to form the connecting rod 20 with a head 24 which is adapted to seat in a recess 25 formed in the locking member and when seated in said recess maintain said locking member in locking position. A spring 26 interposed between the head 24 and the connecting member 22 serves to permit the necessary movement of the connecting rod 20, before the target starts, to release the locking member.

In employing a mount constructed according to our invention and assuming that the target is in upper or firing position, the marker will move the treadle downwardly and with the treadle the connecting rod 20, which will impart movement to the strap 15

and cause movement of the target. As explained above the target will continue under its own momentum to lower or marking position while the strap 15 will reverse itself on the drum. It should be noted that in the lower or marking position the connecting rod 20 will incline rearwardly. After the target has been marked, the marker may return the target to its upper position by again actuating the treadle which will cause movement of the drum in an opposite direction to that movement initially imparted to the same in moving the target from firing position. As in the movement already described, during the movement of the target, the strap 15 will reverse itself, the momentum of the counterweight 17 serving to carry the target to its upper position.

To minimize the twisting stresses that otherwise might be exerted against the guide frame, we have found it preferable to secure the lower cross bar 6 to the post 5 by a single retaining member 27 only. The tendency of a twist in the post to throw the frame out of line with a consequent increase of friction in the guides is thereby obviated.

A target mount of the type described is simple in operation, employs a minimum of parts, is easy and cheap to construct, and will not readily get out of order. It obviates the necessity of hand operated winches or mechanical hoists of the type heretofore employed, and with a device of the type described, the target can be quickly marked and quickly returned to firing position.

Having thus described our invention, what we claim is:

1. In a target mount, a support, guides carried by the support, a target slidably mounted on the guides so as to have limited movement in opposite directions relative to the support, a drum rotatably mounted on the support, flexible means adapted to pass over the drum and having frictional engagement with the same and connected with the target at one end and at the other end to a counterweight, flexible means adapted to be unwound from the drum in one direction to permit an initial movement of the target, said means being of a length equal to substantially half the range of movement of the target so that said means is automatically rewound on the drum in the opposite direction during movement of the target, a rod, a member connected to the last named flexible means slidably mounted on the rod, whereby movement of the rod in one direction causes unwinding of said flexible member, a locking member pivotally mounted on the frame and used to move by gravity to lock the target in one limit of its movement, means on the rod adapted to retain the lock-

ing member in locking position, and resilient means interposed between the last named means and the slideable member.

2. In a target mount, a support, guides carried by the support, a target mounted on the guides so as to have limited movement in opposite directions relative to the support, a drum rotatably mounted on the support, flexible means adapted to pass over the drum and have frictional engagement with the same and connected with the target at one end and at the other end to a counterweight, flexible means adapted to be unwound from the drum in one direction to permit an initial movement of the target, said means being of a length equal to substantially half the travel of the target so that said means is automatically rewound on the drum in the opposite direction during movement of the target, means pivotally connected to the frame adapted to lock the target at one limit of its movement, means adapted to be actuated to unwind the last named flexible means, and means connected to the last named means adapted to retain said locking member in locking position.

3. In a target mount, a support, guides carried by the support, a target mounted on the guides so as to have limited movement in opposite directions relative to the support, a drum rotatably mounted on the support, flexible means adapted to pass over the drum and have frictional engagement with the same, and connected with the target at one end and at the other end to a counterweight, flexible means adapted to be unwound from the drum in one direction to permit initial movement of the target, said means being of a length equal to substantially half the travel of the target so that said means is automatically rewound on the drum in the opposite direction during movement of the target.

4. In a target mount, a support, a target mounted on the support so as to have limited movement relative thereto, in opposite directions, a drum mounted on the support, means connecting the target to the drum to cause rotation of the drum on movement of the target, means adapted to be unwound from the drum in one direction to permit an ini-

tial movement of the target and to be automatically rewound on the drum in an opposite direction during such movement, a locking member for locking the target at one limit of its movement and means connected to said actuating means acting to retain said locking member in locking position.

5. In a target mount, a support, a target mounted on the support so as to have limited movement in opposite directions relative thereto, a drum mounted on the support, means connecting the target to the drum to cause rotation of the drum on movement of the target, means adapted to be unwound from the drum in one direction to permit an initial movement of the target and to be automatically rewound on the drum in an opposite direction during such movement.

6. In a target mount, a movable target, a support for the target, means mounted on the support and adapted to be unwound in one direction to permit movement of the target and means controlled by movement of the target adapted to automatically rewind the first named means in an opposite direction during movement of the target.

7. In a target mount, a supporting frame formed with guides thereon, a target slidably mounted on the guides so as to have limited movement in opposite directions relative to the support, means adapted to be actuated to permit movement of the target and to reset itself automatically during movement of the target, means adapted to automatically lock the target at one limit of its movement, and means connected to the actuating member adapted to cooperate with the locking means to retain said locking means in locking position.

8. In a target mount, a support, a crossbar, a single retaining member adapted to be positioned intermediate the length of the crossbar to secure said crossbar to the support, guides carried by the crossbar at either side the retaining member, a target movable on the guides, and means for moving said target.
